German Design Document No M9300457 of Oct. 10, 1994 in the name of Wilkinson Sword GmbH.

Four (4) photographs of Schick Silk Effects™ Holding Tray and Razor (undated).

Primary Examiner—Sandra L. Morris*Assistant Examiner*—C. Tuttle*Attorney, Agent, or Firm*—Edward S. Podszus**[57]****CLAIM**

The ornamental design for a combined razor handle and holder therefor as shown and described.

DESCRIPTION

FIG. 1 is a perspective view of a combined razor handle and holder therefor as seen from the top, front and right side; FIG. 2 is a perspective view as seen from the bottom, front and right side thereof;

FIG. 3 is a top plan view thereof;

FIG. 4 is a right side elevational view thereof, the left side elevational being a mirror image;

FIG. 5 is a bottom plan view thereof;

FIG. 6 is a front elevational view thereof; and,

FIG. 7 is a rear elevational view thereof.

The broken line showing of the razor cartridge is for illustrative purposes only and forms no part of the claimed design.
